No. 36,765.

Patented February 2, 1904.

UNITED STATES PATENT OFFICE.

ROBERT L. JOHNSON, OF HANLEY, ENGLAND.

DESIGN FOR A COVER-DISH.

SPECIFICATION forming part of Design No. 36,765, dated February 2, 1904.

Application filed January 6, 1904. Serial No. 187,988. Term of patent 3½ years.

To all whom it may concern:

Be it known that I, ROBERT L. JOHNSON, a subject of the King of Great Britain, residing at Hanley, county of Stafford, England, have invented a new, original, and ornamental Design for Cover-Dishes, reference being had to the accompanying drawings.

Figure 1 is a side elevation of a cover-dish embodying the features of my design, and Fig. 2 is a plan view of the same.

What I claim as new, and desire to secure by Letters Patent, is—

The ornamental design for a cover-dish as shown.

In testimony whereof I have signed my name 15 to this specification in the presence of two subscribing witnesses.

ROBERT L. JOHNSON.
